UNITED STATES PATENT OFFICE

HENRY DRESSLER, OF URBANA, OHIO

COMBINED CAN LID RACK AND STERILIZER

Application filed August 4, 1928. Serial No. 297,487.

This invention relates to a combination can lid rack and sterilizer.

The primary object of the invention is to provide a combination of this character, including revolving cages, each designed to hold a large number of milk can tops or the like, and each cage being adjustable to accommodate lids of various sizes.

Another object of the invention is to furnish a can lid rack that will occupy only a small floor space, and which always holds the lids in such position that they may be readily seen at all times.

A further object is to provide a rotatable lid rack having independently rotatable cages in order that the operators may have access to various sized lids at the same time.

Most dairy plants keep their lids in barrels or on stationary shelves, which take up a great deal of room and render the lids inaccessible. It is another object of my invention to eliminate the disadvantages of the old system, and to combine the rack with a sterilizer, in order that the lids may be kept in sanitary condition.

With the foregoing objects outlined and with other objects in view which will appear as the description proceeds, my invention consists in the novel features hereinafter described in detail, illustrated in the accompanying drawings, and more particularly pointed out in the appended claims.

Referring to the drawings,

Fig. 1 is an elevation, partly in vertical section, of my improved rack and sterilizer.

Fig. 2 is an enlarged elevation, partly in vertical section, of the rack.

Fig. 3 is a top plan view of the rack.

Fig. 4 is a horizontal sectional view, taken on line 4—4 of Fig. 2.

Fig. 5 is a top plan view of one of the cages shown detached from the rack.

Fig. 6 is an elevation of one of the cages showing a number of lids held by the same.

Fig. 7 is an enlarged vertical sectional view of a portion of one of the cages, and illustrating the means for swiveling the same to the lower disk of the rack.

Fig. 8 is a similar view illustrating the

means for swiveling the upper end of each of the cages to the upper disk of the rack.

Fig. 9 is a similar view illustrating the manner in which the steam or water pipes are inserted through the upper disk of the rack 55 into the latter.

In describing the invention, I will first refer to the rack which is best shown in Fig. 2. The rack consists of a cast iron base 10 which has a socket 11 in its upper end to receive, 60 with a pressure fit, the lower end of a pipe or rod 12. On the pipe 12, I rotatably mount a lower disk 13, and between the disk and base, a thrust bearing 14 is arranged to permit the disk to freely rotate.

A sleeve or pipe 15 is slid on to the pipe 12 from its upper end, and functions as a spacer for the upper disk 16 which has a whole 17 at its center to receive the upper end of the pipe 12.

For the purpose of rigidly connecting the upper and lower disks, I have provided each disk with six holes, to receive threaded rods 18 which have their ends connected to the disks by nuts 19; an upper and lower nut 70 being provided at each end of the rod, so as to clamp the disks in position. Each rod 18 is surrounded by a spacing sleeve 20, as best shown in Fig. 9, for the purpose of spacing the upper and lower disks.

Between the disks, I mount the cages 21, one of which is shown detached in Fig. 6. Each cage also consists of a lower disk 22, an upper disk 23, and threaded rods 24. The rods are connected by pairs of nuts 25 to the 85 disks, and sleeves 26 surround the rods for spacing purposes.

In order that the rods may be adjusted toward and away from the axis of the disks, to accommodate can tops 27 of various sizes, 90 each rod 24 extends through curved slots 28, arranged in the disks 22 and 23. Each slot is preferably arc-shaped, and one end of the same is arranged nearer the periphery of the disk than the other end of the slot.

Each cage is attached to the disks 13 and 16 by swivel connections, and as best shown in Figs. 7 and 8, the lower cage disk 22 has a depending trunnion 29 which fits in a step bearing 30 on the lower disk 13, and may be 100

mounted on anti-friction balls 31. After the lower trunnion has been inserted in its step bearing 30, an upper trunnion 32 on the disk 23, will be in alignment with a vertically adjustable bearing member 33 arranged on the cage disk 16, and when the bearing 33 is adjusted, the cage will be secured in a rotatable manner in the rack.

From the foregoing, it may be seen that this rack will hold can lids of various sizes, and the whole rack may be rotated, as well as any one of the cages. As there are frequently two or three men taking lids out of the rack at the same time, and one or two men putting lids in, it will be recognized that the revolving features of the rack have an advantage, for instead of it being necessary to turn the whole machine, either cage may be turned, so that the operators will have free access to the various lids.

I have designed this rack with a view of combining the same with a sterilizer, and to this end, the upper disk of the rack, as shown in Fig. 3, is provided with three holes 34, 25 designed to receive perforated steam pipes 35 which are rigidly mounted in a vertically movable hood 36. This hood is normally held in an elevated position, and out of the way, by means of a cable 37, which passes 30 over guide pulleys 38 and 39, that may be supported on the ceiling and wall of the room in which the device is located. The free end of the cable may be wound on a suitable support or hook 40 secured to the side wall. 35 Steam is fed to the pipes 35 by means of a flexible hose 41 that is attached to a pipe 42, having a control valve 43.

The lower end of the hood is designed to make close contact with the lower disk 13, 40 and for this purpose, the lower disk is of larger diameter than the upper disk 16, and the lower edge of the hood is provided with a ring 44, formed of angle iron or the like. A cork washer 45 is secured to the ring 44, 45 and is designed to engage the upper surface of the disk 13.

The lower edge of the hood and the lower disk may be secured together by any suitable fastening means, such as hooks 46.

50 When the device is to be used as a sterilizer, sanitary pipe valves, cream separator parts, etc., may be placed on the shelves or disks, in addition to the can lids, and after the hood has been lowered and secured in 55 position, as shown in Fig. 1, the steam may be turned on. Any condensation may escape through holes 47, (Fig. 4), provided in the lower disk.

The device may be used for washing purposes, by introducing water through the pipe 42, instead of steam.

From the foregoing, it is believed that the construction, operation and advantages of the invention may be readily understood, 65 and I am aware that changes may be made

in the details disclosed, without departing from the spirit of the invention, as expressed in the claims.

What I claim and desire to secure by Letters Patent is:

70 1. In a sterilizer, a base, a hood, spaced rotatable disks mounted on the base within the hood, and cages rotatably mounted between the disks.

75 2. In a sterilizer, a base, a hood, spaced disks rotatably mounted on the base within the hood, and cages rotatably mounted between the disks, each cage including rods, and means for adjusting said rods toward or away from the axis of rotation of the 80 cage, and for fixing the rods in various positions.

85 3. In a sterilizer, upper and lower rotatable disks, cages attached to the disks by swivel connections, and including a pair of 90 disks, each disk of the pair having a plurality of slots, one end of each slot being arranged nearer the periphery of the disk in which it is located, than the other end of the slot, rods passing through said slots and joining the pair of disks, and means for adjustably securing the rods to the pair of disks.

95 4. In a sterilizer, a base, an axle having its lower end fixed to the base, a hood, spaced disks rotatably mounted on the axle within the hood, a thrust bearing arranged between the lower disk and base, a spacing sleeve surrounding the axle and arranged between the disks, and a plurality of cages rotatably mounted between the disks, the ends of the 100 cages having swivel connections with the disks.

105 5. In a sterilizer, a base, an axle carried by the base, upper and lower disks rotatably mounted on the axle, rod like members connecting and spacing the disks, and cages swiveled to said disks, each cage including a pair of disks, each provided with slots, each slot having one of its ends arranged nearer the axis of the disk in which it is positioned, than its other end, rods passing through the slots, and means for fixing the rods in various positions along the slots.

110 6. In combination, a floor supported rotatable rack having a disk provided with perforations arranged about the axis of rotation, a vertically movable hood to enclose the rack, means for raising and lowering said hood, pipes of substantially the same height 115 as the hood rigidly mounted in the latter and positioned to enter the perforations when the hood is lowered, and means including a flexible pipe for leading a fluid to the hood.

120 7. In a sterilizer, a base, a hood resting on the base and forming with the latter a closed casing, spaced rotatable disks mounted on the base within the hood, and cages rotatably mounted between the disks, each cage including a plurality of vertical bars spaced 125 130

apart a sufficient distance for the introduction of milk can tops into the cage.

8. A sterilizing apparatus comprising a rack rotatable about a vertical axis and having a top disk provided with perforations spaced from said axis, a hood, means for use in moving the hood toward or away from the rack and to a position to enclose the rack, spaced perforated pipes rigidly connected to the hood, positioned within the latter and extending downwardly into close proximity to the bottom edge of the hood, said pipes being positioned to enter the perforations of said disk when the hood is lowered, and means for introducing a fluid into said pipes.

HENRY DRESSLER.
